UNITED STATES PATENT OFFICE

143,983

DESIGN FOR A ROLLER SKATE

Anthony J. Miller, Chicago, Ill.

Application August 9, 1945, Serial No. 121,330

Term of patent 14 years

(Cl. D34—14)

To all whom it may concern:

Be it known that I, Anthony J. Miller, a citizen of the United States, residing at Chicago, in the county of Cook and State of Illinois, have invented a new, original, and ornamental Design for a Roller Skate, of which the following is a specification, reference being had to the accompanying drawing, forming part thereof.

In the drawing,

Fig. 1 is a side elevation of a roller skate embodying my new design;

Fig. 2 is a bottom view thereof omitting the parts shown in dotted lines in Fig. 1;

Fig. 3 is a front elevation thereof; and

Fig. 4 is a sectional view taken on the line 4—4 of Fig. 2.

The essential features of my design reside in the parts shown in full lines on the drawing.

I claim:

The ornamental design for a roller skate, substantially as shown and described.

ANTHONY J. MILLER.
